By E. S. Woaman Co.,
Attn: Attorney S.

UNITED STATES PATENT OFFICE.

CHARLES C. McCOMBS, OF STEPHENVILLE, TEXAS.

CHECK PROTECTOR.

1,423,236.

Specification of Letters Patent. Patented July 18, 1922.

Application filed November 19, 1921. Serial No. 516,378.

To all whom it may concern:

Be it known that I, CHARLES C. McCOMBS, a citizen of the United States, residing at Stephenville, in the county of Erath and 5 State of Texas, have invented certain new and useful Improvements in Check Protectors, of which the following is a specification, reference being had therein to the accompanying drawings.

10 This invention relates to a check protector, and the object is the production of a simple and efficient pocket device that will enable the user to protect a check so that it cannot be fraudulently changed or altered, nor can 15 the signature of the maker of the check be torn off the check, or duplicated in any way without injury to the check or the defacement thereof.

With this and other objects in view, my 20 invention comprises certain novel combinations, constructions and arrangements of parts as will be hereinafter described, illustrated in the accompanying drawings, and more particularly pointed out in the ap-

25 pended claims.

In the drawings:

Figure 1 is a view, in elevation, of one side or back of my device.

Figure 2 is an edge view of the device.

30 Figure 3 is a central, sectional view of the device.

Figure 4 is a view, in elevation, of the back or bottom of the device with the numeral rings removed, while

35 Figure 5 is a central, sectional view of the back of the casing shown in Fig. 4.

Figure 6 is a view, in elevation, of the retaining ring of the device, while

40 Figure 7 is a central, sectional view of the same.

Figure 8 is a view, in elevation, of the inside of the front or top of the casing of my device, while

45 Figure 9 is a central, sectional view of the same.

Figure 10 is a view, in elevation, of the inside of the ink-pad device, while

50 Figure 11 is a central, sectional view of the same.

Figure 12 is a view, in elevation, of the outer numeral ring, while

Figure 13 is a central, sectional view of the same.

Figure 14 is a top plan view of the device

shown in position on a check for forming 55 "Not over \$10\$" over (the place for) the signature of the maker of the check.

Referring to the drawings by numerals, 1 designates the casing which comprises a bottom 2 and a top 3; the top and bottom of the 60 casing 1 are connected, at 4, leaving a slit-like opening 5 between the top and bottom of the casing, into which slit-like opening the check 6 (Fig. 14) is placed.

In the bottom of the casing 2, I place a 65 plurality of numeral rings 7 and around these numeral rings is an outer numeral ring 8. Each ring is provided with a lug 9 which enables the operator to turn the rings within the casing 1 for placing the desired numerals 70 in transverse alignment to form the desired number to be printed or otherwise exposed upon the check; dollar signs may be placed in front and back of numerals, such as 75 "\$10\$" shown in dotted lines in Fig. 14, or a dollar sign may be exposed before the numeral, by merely rotating the rings within the casing.

The outer numeral ring 8 is retained in 80 position by bearing ring 10, which bearing ring is suitably fastened in the bottom of the casing contiguous to the slit-like opening 5. Positioned within the casing and fastened against the inner face of the bottom 2, is a die or plate 11; this plate 11 is fastened by 85 rivets 12, Figs. 1 and 3, and on this plate 11 is formed the words, "Not over." Plate 11 is provided with a flanged edge (Fig. 3) which overlaps or overhangs the inner numeral ring 7, whereas, the bearing ring 10 90 overhangs the flanged edge 10^a of the outer numeral ring 8, Figs. 3 and 13. By reason of the bearing ring 10 and the plate 11, the numeral rings are securely fastened within the casing 1, but are free to rotate one upon 95 the other within the casing for placing any desired numerals or dollar signs in alignment with the fixed words, "Not over," on the central plate 11.

In the top 3, of the casing 1, is formed a 100 large, central, opening 13, into which opening projects the ink-pad device 14. This device 14 comprises a springy cap 15, provided with a flanged edge 16; the edge 16 extends under the top 3, Fig. 3, and retained in the 105 cap is an ink-pad 17. The pad 17 is provided with an elongated projection 18, which projection extends at its outer end 19 beyond the

edge of the cap, so that this projecting end 19 will allow the efficient inking of the numeral or dollar sign on the outer numeral ring 8 when the device is in use, for protecting a 5 check, as shown in Fig. 14.

A retaining ring 20 is placed in the casing 1 against the top 3. This retaining ring is provided with a large, central opening 13^a to allow the springy cap to be pressed down 10 sufficiently to cause the projection 18 on the pad 17 to engage the aligned letters and numerals at the will of the operator. The retaining ring has an annular socket 21 in which the ink-pad device 14 is seated (Figs. 15 3 and 7) and a filler guard 22 is formed upon the retaining ring 20, filling the space between the numeral rings and cap at the portion 4 of the casing 1. A slot 23 is formed in the retaining ring into which the projecting end 19 of the projection 18 of the pad 17 extends; this projecting end 19 extends over all the numerals and dollar signs on the numeral rings that are in alignment with the words "Not over."

25 The retaining ring 20 is fastened within the casing 1 by rivets, as shown at 24, Fig. 2.

In operation, the check to be protected is inserted in the slit-like opening 5; then the operator, if he has not already done so before, turns the rings to place the desired numerals in alignment with "Not over", then the words and the aligned numerals are positioned against the check 6, either across the check or across or parallel with 35 the signature on the check, then the springy cap 15 is pressed upon, pressing the projection 18 against the check whereupon the check will be perforated by the numerals and words that are in alignment, causing the aligned 40 numerals and words to be printed or exposed by small perforations upon the check. By this procedure, the signature of the check cannot be changed, nor the amount for which the check is made altered, nor can the check 45 be torn to remove the signature, to allow an expert or fraudulent person to trace over the signature with a view to fraudulently copying the signature onto a new check.

While I have described the preferred embodiment of my invention, and have illustrated the same in the accompanying drawings, certain minor changes or alterations may appear to one skilled in the art to which this invention relates, during the extensive 55 manufacture of the same and I, therefore, reserve the right to make such alterations or changes as shall fairly fall within the scope of the appended claims.

What I claim is:

60 1. In a device of the class described, the combination of a split casing, numeral rings in said casing to one side of said split, and an inking pad in the other side of said casing to said split, whereby a check placed in 65 the split of the casing can be operated upon

to expose certain numerals upon the check when the pad is pressed toward the numerals.

2. In a device of the class described, the combination of a casing provided with a 70 slit-like opening in its center, printing and perforating means in said casing at one side of said opening, and yielding inking means in said casing at one side of said opening cooperating with said printing and perforating means.

3. In a device of the class described, the combination of a casing provided with a 80 check-receiving opening, numeral or symbol rings in said casing contiguous to said opening, means fastening said rings within said casing, a springy cap provided with an inking pad in said casing to one side of said opening, and means fastening said springy cap in said casing.

4. In a device of the class described, the combination of a casing provided with a check-receiving opening, a bearing and a fixed plate in said casing to one side of said opening, numeral and symbol rings rotatably mounted in said casing and retained by said bearing ring and plate, said plate provided with designating means, and a movable pad device in said casing at the opposite side to that containing the rings and 95 plates for pressing upon aligned words, numerals and symbols.

5. In a device of the class described, the combination with a casing provided with a check-receiving opening, of letter and numeral forming means in said casing to one 100 side of said opening, a pad device in the casing at the other side of said opening, said pad device comprising a springy cap containing a pad, means holding said pad device in the casing against displacement, and said pad device adapted to be depressed for operating against a check and upon aligned characters of said letter and numeral forming means.

6. In a device of the class described, the combination of a casing provided with a check-receiving opening, letter or character forming means in said casing to one side of said opening, a yieldable pad device in said 115 casing at the opposite side of said opening, a retaining ring in the casing and against said pad device, and said retaining ring provided with a filler guard interposed between the pad device and a portion of said letter 120 or character forming means.

7. In a device of the class described, the combination of a casing provided with a slit-like opening, numeral or character forming means in said casing to one side of said opening, a pad device in the casing at the opposite side of said opening, a retaining ring in said casing against said pad device, said retaining ring provided with a large 125 central opening and with a side slot, said 130

pad device comprising a cap and a pad, and said pad provided with a projection extending at one end beyond the pad and cap and into said side slot whereby when the device 5 is in operation the projection of the pad will press upon aligned numerals or characters. 8. In a device of the class described, the combination of a casing provided with a check-receiving opening, overlapping char- 10 acter forming rings within said casing at one side of said opening, and yieldable means in the casing at the other side of said opening for pressing upon said numeral or character forming rings to produce certain characters or numerals upon a check or sheet 15 positioned in the opening.

In testimony whereof I hereunto affix my signature.

CHARLES C. McCOMBS.
